(57) **CLAIM**

The ornamental design for a signature light arrangement for a taillight, as shown and described.

DESCRIPTION

FIG. 1 is a front left perspective view of a signature light arrangement for a taillight according to the present invention.

FIG. 2 is a front view thereof.

FIG. 3 is a left side view thereof; and,

FIG. 4 is another front view thereof shown in use.

In FIGS. 1-3, the signature light arrangement is shown as part of the taillight within the broken lines, and the rest of the taillight located outside of the broken lines is shown in de-emphasized and half-tone portions to show environmental structure, which forms no part of the claimed design. The broken lines illustrating environmental structure in FIG. 4 form no part of the claimed design.
